INVENTOR

John T. Hattersley,
BY *Chas. O. Gill*
ATTORNEY

UNITED STATES PATENT OFFICE.

JOHN T. HATTERSLEY, OF NEWARK, NEW JERSEY, ASSIGNOR TO THE
ALBERENE STONE COMPANY, OF NEW YORK, N. Y.

WASHTUB.

SPECIFICATION forming part of Letters Patent No. 633,647, dated September 26, 1899.

Application filed July 6, 1898. Serial No. 685,233. (No model.)

To all whom it may concern:

Be it known that I, JOHN T. HATTERSLEY, a citizen of the United States, and a resident of Newark, in the county of Essex and State of New Jersey, have invented certain new and useful Improvements in Washtubs, of which the following is a specification.

The invention relates to improvements in washtubs, and pertains more particularly to improvements in what are known as "stationary" washtubs, which are customarily connected with a water-supply system of piping.

The invention comprises certain improvements in the apparatus for supplying the water to the several compartments of the wash-tub, as hereinafter fully explained, and particularly pointed out in the claims.

The object of the invention is to improve the construction, appearance, and efficiency of the stationary stone tubs and to increase their convenience of use.

The invention will be fully understood from the detailed description hereinafter presented, reference being had to the accompanying drawings, in which—

Figure 1 is a perspective view of a stationary two-compartment stone washtub constructed in accordance with and embodying the invention. Fig. 2 is an enlarged vertical transverse section of same, taken partly through the partition by which the tub is divided into the two compartments. Fig. 3 is an enlarged horizontal section of a portion of same, taken on the dotted line 3 3 of Fig. 2 and indicating by the dotted line 2 2 the section on which Fig. 2 is taken; and Fig. 4 is an enlarged detached section of a portion of the tub on the dotted line 4 4 of Fig. 1 and showing more particularly the manner of uniting, by means of a slip-tongue and cement, the meeting edges of the stone sections which compose the sides or other parts of the tub.

In the drawings, A designates the stone tub as a whole, and this tub, as usual, has the front and rear sides B C, ends D, bottom E, and partition F, the latter subdividing the tub into the compartments G H. The side or sides of the tub are formed of the several stone sections *a a a*, whose vertical meeting edges are at opposite sides of the plane of

the partition F and are effectually secured together with proper trueness and in a liquid and steam tight manner by means of the vertical metallic slip-tongues I, one of which is illustrated more clearly in Fig. 4, in which it will be observed that the slip-tongue is a plain concealed strip of metal entering at its opposite edges the grooves J J in the meeting edges of the stone sections *a a* and being securely fastened within said grooves by means of the cement or like material K.

The slip-tongues I, which connect the sections *a* of the sides of the tub, will extend from the upper to the lower edges of said sides, and hence are concealed throughout their length and operate throughout their length in the securing of the sections *a* together. The width of the slip-tongues I is such in relation to the depth of the grooves J that the edges of the stone sections *a* will closely contact with one another, and hence when the slip-tongues I are in place they create no separation of the stone sections *a* and extend lengthwise of the joint between said sections.

The sides of the tub will be fastened in the usual manner to the ends, bottom, and central partition of the tub, and the sections composing said sides will, as above explained, be secured together in a liquid and steam tight manner by means of the slip-tongues I. The slip-tongues I insure the accurate alinement with one another of the stone sections *a* and the formation of liquid and steam tight joints between said sections. The cement K will readily harden within the grooves J and about the tongues I, and the side of the tub when thus constructed of the several sections *a* becomes as efficient and durable as though in a single piece of material. The ends of the tub may also be formed in sections united at their meeting edges by the slip-tongues I; but since this feature of the construction is clearly illustrated with respect to the sections *a* composing the sides of the tub it will be unnecessary to refer especially to the end sections, since the means illustrated for securing the side sections of the tub together are equally applicable to the securing together of the sections composing the ends of the tub.

The upper edges of the tub will, as usual, be provided with lugs L of any suitable con-

struction to receive the wood framing, which is customarily applied to the upper edges of the tub as a finish for the same. This wooden frame will cover the upper ends of the grooves 5 J and slip-tongues I, and hence when the tub is in position neither the slip-tongues nor the grooves will be discernible.

My invention pertains particularly to the 10 apparatus for supplying water to the compartments of the tub, and in accordance with this invention I provide upon the ends of a single water-supply pipe M the coupling N to receive two faucets O P, one being at each side of the central partition F. It may be 15 assumed that the pipe M is intended for the supply of cold water, and it will be apparent that with the construction shown the pipe M may be utilized to supply cold water to either one of the compartments G H or to both of 20 said compartments at the same time. The pipe M is in the central vertical plane of the partition F, and the coupling N on the end of said pipe extends transversely of the partition F, whereby the faucets O P are brought 25 directly over the compartments G H in close relation to the opposite faces of said partition F. In all instances in which it is desirable to supply both hot and cold water to the tub I provide the additional pipe Q, which will 30 be connected with the hot-water supply and is on its end provided with the coupling R, which extends transversely of the partition F and is provided with the faucets S T, by which one or both of the compartments G H may be 35 supplied with hot water from the one pipe Q. The pipe Q is also in the central vertical plane of the partition F, and hence the faucets S T, connected with the coupling R, are brought directly over the compartments G H 40 and in close relation to the opposite faces of the central partition F. In the preferred construction of this portion of my invention I cause the pipes M Q to be extended through apertures m q, respectively, in the rear side 45 of the tub and through the central partition F to the transverse apertures r s in the said partition. The couplings N R are passed endwise into the apertures r s, and when therein they first receive the ends of the pipes 50 M Q and thereafter the faucets, which, as shown, possess the flanges t, which contact with the faces of the partition F and effectu-

ally conceal the ends of the couplings N R, and also the ends of the apertures r s. I do not limit the invention in all instances to the 55 concealing of the couplings N R within the central partition F, but regard this feature of the construction as very desirable and as embracing a portion of my invention. The arrangement of the pipes M Q, couplings N 60 R, and faucets O P and S T above described presents a very great advance over the methods and means heretofore in use for supplying hot and cold water to washtubs.

What I claim as my invention, and desire 65 to secure by Letters Patent, is—

1. The stationary washtub having the solid slab partition F subdividing the same into the compartments G, H, and having the transverse aperture r, and the back C of said 70 tub having the aperture m in line with said partition F and at right angles to the said aperture r, combined with the water-supply pipe M extending through said aperture m to the said aperture r, the threaded coupling 75 N in said aperture r and engaged by the end of said pipe M, and the faucets O, P, having the flanges t engaging the ends of said coupling, said flanges concealing the ends of said coupling and said aperture r; substantially 80 as and for the purposes set forth.

2. The stationary washtub having the solid slab partition F subdividing the same into the compartments G, H, and having the parallel transverse apertures r, s, and the 85 back C of said tub having the apertures m, q, in line with said partition F one below the other and at right angles to said apertures r, s, combined with the water-supply pipes M, Q, extending respectively through said 90 apertures m, q, to said apertures r, s, the threaded couplings N, R, within said apertures r, s, and respectively engaged by the ends of said pipes M, Q, the faucets O, P, on the ends of said coupling N, and the faucets S, T, on the ends of said coupling R; substantially 95 as and for the purposes set forth.

Signed at New York, in the county of New York and State of New York, this 2d day of July, A. D. 1898.

JOHN T. HATTERSLEY.
